CHAIR

John H. Risley, Waterville, Maine

Application November 26, 1952, Serial No. 22,451

Term of patent 14 years

(Cl. D15—8)

To all whom it may concern:

Be it known that I, John H. Risley, a citizen of the United States and a resident of the city of Waterville, in the county of Kennebec and State of Maine have invented a new, original, and ornamental design for a Chair, of which the following is a specification, reference being had to the accompanying drawing forming a part thereof.

On the drawing:

I claim:

The ornamental design for a chair, as shown.

JOHN H. RISLEY.
